ROTARY VALVE.

1,161,813.

Specification of Letters Patent. Patented Nov. 23, 1915.

Application filed December 6, 1913. Serial No. 805,019.

To all whom it may concern:

Be it known that I, LOUIE A. SHERMAN, a citizen of the United States, residing at Kansas City, in the county of Jackson and State of Missouri, have invented certain new and useful Improvements in Rotary Valves; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to a rotary valve for explosion engines, and has for its principal object to provide a device of that character whereby the intake and exhaust of the engine cylinder is delivered through a common port in the valve member, at properly spaced intervals relative to each other and to the operation of the spark device.

It is also an object of the invention to provide the valve with a packing member, 25 which may automatically adjust itself to insure close contact against the cylinder wall to prevent the escape of live or exhaust gases about the periphery of the valve at the sides of the valve port.

30 In accomplishing these objects I have provided improved details of structure; the preferred forms of which are illustrated in the accompanying drawings, wherein:—

Figure I is a perspective view of an engine equipped with a rotary valve, constructed in accordance with my invention.

Fig. II is a central, longitudinal section of the engine cylinder and valve, with its operating mechanism. Fig. III is an end view 40 of the cylinder head detached from the cylinder. Fig. IV is a transverse section on the line IV—IV, Fig. II. Fig. V is a detail perspective of the valve. Fig. VI is a similar view of the expansible valve ring.

45 Referring more in detail to the parts:—
1 designates an explosion engine cylinder, which is mounted on a bed 2, and provided with a piston 3, having a connecting rod 4 leading to a crank shaft 5, which is provided with the ordinary fly-wheel 6. Fixed on the cylinder 3 is a head 8, both the cylinder and head having water jackets 9 communicating through ports 10 in the head flange 11 and fed through the circulating pipes 12—13. The cylinder head is provided with

an intake port 15 which communicates with a carbureter 16 and has an exhaust port 18 spaced from the intake port and provided with a conduit 19 for conducting the exhaust to a distance from the engine.

60 Revolubly mounted in the head 8 is a valve 21 comprising a ring which fits snugly within the head chamber and has an interior web 22 extending thereacross and preferably formed integral therewith. Fixed rigidly to the web 22, in any suitable manner, is a rod 23 which extends through a stuffing box 24 in the end of the head and is connected with a gear wheel 25 that meshes with a pinion 26 on a shaft 27 that is journaled in bearing 28 on the cylinder head and the bed of the engine, and has a beveled gear wheel 29 meshing with a mating gear 30 on the crank shaft 5. The valve ring 21 has an annular groove 32 therein, and located within the groove 32 is a port 33, adapted for registration with the intake and exhaust ports 15—18. Integral with the ring 21, and projecting into the groove 32, from one edge thereof, is a lug 34. Seated loosely within the groove 32 is an expansion ring 35, having a socket 36 into which the lug 34 on the valve ring is projected to hold the ring against rotary movement on the valve, but without interfering with its expansion and contraction. The ring 35 has a port 38 held in registration with the valve port 33 by the lug and socket connection between the ring and valve; the ring being preferably broken at the sides of the port, as illustrated in the drawings.

70 The head of the cylinder carries a sparking device 40, having a circuit wire 41 leading thereto and connected with any suitable source of current (not shown). Mounted on the cylinder head is an arm 43, having a brush 44 wiping a commutator 45 on the valve rod 23, and having a circuit wire 46 also leading to the current supply; the arm 43 being insulated from the cylinder head and the bed 2 having a wire 47 grounded thereon to complete a primary circuit through the cylinder head, so that when the brush contacts a certain point on the commutator, the primary circuit is closed and the secondary circuit induced through the spark to produce the exploding spark; it being apparent that the spark may be located at such a position relative to the intake and exhaust ports that a charge may 75 80 85 90 95 100 105 110

be exploded when the piston is in the proper position.

In using the device, presuming the parts to be constructed and assembled as described, 5 when the engine is in operation, the valve is revolved through its driving connection with the crank shaft to bring the valve port into registration with the intake port in the cylinder head to take in a charge. After 10 the charge has been taken in, the secondary circuit is closed to explode the charge and drive the piston through its working stroke. After the driving stroke of the piston is completed, the valve port registers with the 15 exhaust port in the cylinder head to clean the cylinder.

By providing the valve with the expandable ring, the ring takes up wear of the valve so that a tight joint is always present 20 between the valve and cylinder, thereby obviating by-pass of the intake charge or exhaust from the valve port into the cylinder and about the rotary valve.

It is apparent that, with this construction, 25 the valve may have a loose fit in the cylinder to provide for easy reciprocation, as the ring prevents the escape of live and ex-

haust gases between the valve and cylinder head, and as all of the valve ports are mounted in the head of the cylinder, they 30 may be easily replaced or repaired when the head is removed.

Having thus described my invention, what I claim as new therein, and desire to secure by Letters-Patent, is:— 35

A rotary valve comprising a cylinder, a separate head attached to the cylinder and having an intake chamber communicating with the cylinder chamber and having spaced ports in its circumference, a body 40 ring revolubly mounted in said head and having a single port adapted for communication with either of the head ports and having a circumferential groove, an expansion ring seated in the groove and having 45 an opening in constant communication with the ring port, and means for revolving the body ring from the exterior of the head.

In testimony whereof I affix my signature in presence of two witnesses.

LOUIE A. SHERMAN.
